UNITED STATES PATENT OFFICE.

WILLIAM A. EDWARDS, OF CHICAGO, ILLINOIS, ASSIGNOR OF TEN PER CENT TO
 IRA J. WILSON, AND ONE-HALF TO CHARLES E. REED, BOTH OF CHICAGO,
 ILLINOIS.

OILING SYSTEM.

Application filed March 21, 1921. Serial No. 454,274.

To all whom it may concern:

Be it known that I, WILLIAM A. EDWARDS, a citizen of the United States, residing at Chicago, in the county of Cook and State of Illinois, have invented new and useful Improvements in Oiling Systems, of which the following is a specification.

This invention relates in general to oiling systems, and more particularly to systems applicable to gas engines.

Ford cars and many other makes of automobiles rely for their engine lubrication upon what is known as a "splash" system of oiling, and with such a system, it is highly desirable to maintain a definite, predetermined oil level in the crank case, for if the level becomes too low, the engine suffers from insufficient lubrication, and if the oil level is too high, too much oil is thrown into the cylinders beneath the pistons, where it works up around the rings, causing carbon deposits on the cylinder walls and in the combustion chamber, and also resulting in fouling of the spark plugs. The most efficient and desirable operation of the engine can be secured only when the oil in the crank case is maintained at a definite predetermined level, but in actual practice, this desideratum has been, so far as I am aware, unattainable, since if the crank case is filled before starting the run only to the desired level, the oil will soon fall below that level and will continue to diminish in quantity until at the end of the long run the motor is receiving insufficient lubrication. On the other hand, should sufficient oil be supplied to the crank case to insure lubrication throughout a long run, there will of necessity be a considerable surplus at the beginning of the run, which is objectionable for the reasons heretofore stated.

One of the primary purposes of my present invention is to provide a system which will automatically maintain the oil in the crank case at a desired predetermined level, which is most conducive to efficient and satisfactory performance of the motor.

Another purpose of my invention is to provide a system which will automatically take care of variations in the oil level resulting from elevation or depression of the front end of the motor, as in ascending or

descending hills and grades, and with this purpose in view, my invention is designed when the engine is going downhill, to admit 55 to the crank case additional oil in sufficient quantities to insure lubrication of the engine and adjacent parts, and when the level of the engine is again restored, will withdraw from the crank case this additional 60 oil, which is then undesirable surplus, and will store it in a reservoir for future use, when required. Furthermore, in ascending a grade or hill, which causes the front end 65 of the engine to be elevated, the oil accumulates in the rear portion of the crank case, with the result that not infrequently, the forward cylinders receive so little lubrication that injury to the motor occurs. My invention, however, is designed to withdraw 70 the surplus from the rear of the crank case, under these conditions, and to return it to the forward portion of the crank case so that the forward cylinders will always receive sufficient lubrication, while the rear 75 portion of the crank case is relieved from an abnormal and undesirable high oil level.

Other objects and many of the attendant advantages of my invention should be readily appreciated as the same becomes better 80 understood, by reference to the following description, when considered in connection with the accompanying drawings.

Referring to the drawings:

Fig. 1 is a side elevation of a gas engine 85 equipped with my invention;

Fig. 2 is a transverse sectional view, somewhat diagrammatic in character, of the construction shown in Fig. 1;

Fig. 3 is a detail of one pipe connection 90 to the oil reservoir; and

Fig. 4 is a fragmentary sectional view showing the connection of one of the pipes to the crank case and the valve with which it is equipped.

On the drawings, reference character 5 indicates generally the crank case, 6 the cylinder block, and 7, the intake manifold of a gas engine of any well known or preferred type, that illustrated being the engine commonly used in a Ford automobile where the crank case also houses the transmission and brake mechanisms. The crank case in this instance is as usual provided at its bottom

with a plurality of pockets 8, one beneath one end with the upper portion of the reservoir 12 and its other end with the crank case on the line of the desired oil level, and to insure the exposure or uncovering of the whole cross sectional area of the pipe 18 when the oil level in the crank case falls below the connection, the inner end of pipe 18 is preferably downturned, as indicated at 19 so that the exposed end is disposed in a horizontal plane.

For the purpose of carrying a reserve or surplus of lubricating oil which will be delivered to the crank case as required, I mount in some convenient location at a higher level than the crank case, and in the present instance upon the dash board 11 of the car under the hood of the engine, a reservoir 12 supported by a bracket 10, or other convenient means of support. This reservoir is preferably equipped with an oil gauge or indicator of any preferred construction, the form shown for purposes of illustration comprising an indicator finger 13 adapted to travel over a scale 13', the indicator being controlled by a float disposed within the reservoir. This indicator, as shown, is disposed on the rear face of the dash board, where it may be observed by the driver. Any other form of gauge may be employed, if preferred.

The oil reservoir is connected with the intake manifold 7 of the engine by a pipe 14 through which suction is exerted upon the reservoir to create a vacuum, or partial vacuum therein, and the rapidity with which the vacuum will be produced is determined by a restricted passage 15 in the connection between the reservoir and the pipe 14, as shown in Fig. 3.

Oil is delivered from this reservoir into the crank case through a pipe or tube 16, which may be connected to the crank case at any point between the front and rear ends thereof below the desired oil level therein, but preferably, it is connected at the forward end of the crank case so that when the car is ascending a steep grade, which causes the oil to flow to the rear end of the crank case, leaving the pockets 8 unsupplied with oil, the oil delivered from the reservoir to the forward end of the crank case will flow into these pockets and thereby insure adequate lubrication of the connecting rods and bearings. In order to prevent the breaking of the vacuum in the reservoir 12 induced through the pipe 14, when the car is ascending a grade so that the delivery end of the pipe 16 will be uncovered, I prefer to equip this end of the pipe with a check valve 17, which will permit flow of oil from the reservoir to the crank case, but will preclude return flow of oil or of air from the crank case into the reservoir.

Another pipe or tube 18 is connected at

ating a surplus which insures adequate lubrication of the cylinders when otherwise the slowly moving cranks would fail to splash sufficient oil. Furthermore, when the motor is stopped, all the oil will drain into the crank case, creating a desirable surplus which will be splashed against the dry cylinder walls which have also drained off while the motor was idle, thereby insuring immediate lubrication of the walls as soon as the motor is started.

It is believed that my invention, and many of its inherent advantages will be understood from the foregoing without further description, and it should be manifest that the device is extremely simple in construction, is not liable to get out of order, is cheap to manufacture and easy to install, and while I have shown and described a preferred embodiment thereof, obviously, my invention may be embodied in structures differing materially in their details from that shown and described, without departing from the essence of the invention as defined in the following claims.

I claim:

1. An oiling system, comprising an oil case an oil surplus reservoir, a pipe in continuous communication with said reservoir through which suction is continuously exerted upon said reservoir, a pipe connected with said reservoir through which oil is delivered from said reservoir when vacuum therein is broken, and a pipe connected with said reservoir through which the vacuum in said reservoir is controlled by the oil level in said case.

2. The combination with a gas engine, including a crank case and an intake manifold, of a surplus oil reservoir, a connection between said manifold and said reservoir for exerting a continuous suction thereon, a connection between the bottom of said reservoir and said crank case for delivering oil to the crank case, and a connection between the upper portion of said reservoir and said crank case at the desired oil level therein through which oil will be withdrawn from the crank case into said reservoir when the oil level in the crank case covers said connection and through which the vacuum in said reservoir will be relieved when the oil level in the crank case is below said connection.

3. The combination with a gas engine, including a crank case and an intake manifold, of a surplus oil reservoir, a connection between said reservoir and said crank case below the desired oil level in the crank case, a second connection between said reservoir and said crank case at the desired oil level therein through which air or oil will be drawn from the crank case into the reservoir to maintain said desired oil level in the crank case, and a connection between said reservoir

and said manifold through which suction is continuously applied to the reservoir.

4. The combination with a gas engine, of an oil reservoir, a pipe for delivering oil from said reservoir to the crank case of the engine, a pipe establishing communication between the upper portion of said reservoir and the crank case at the desired oil level therein, and means for exerting a continuous suction upon said reservoir.

5. The combination with a gas engine, of an oil reservoir, a pipe establishing communication between the upper portion of said reservoir and said crank case at the desired oil level therein, a pipe for delivering oil from said reservoir to said crank case, and means for continuously exerting a suction upon said reservoir.

6. The combination with a gas engine including a crank case and an intake manifold, of a surplus oil reservoir, a pipe through which continuous communication is established between the upper portion of said reservoir and said manifold, a pipe communicating with the upper portion of said reservoir and with said crank case at the desired oil level therein through which pipe suction is exerted from said reservoir upon said crank case, and an oil delivery pipe leading from the lower portion of said reservoir to said crank case below the desired oil level therein through which oil is delivered from said reservoir to said crank case when the vacuum in said reservoir is broken through said suction pipe.

7. The combination with a gas engine comprising a crank case, of a closed surplus oil reservoir, means for delivering oil from said reservoir to said crank case to establish a predetermined level therein, and independent means for returning excess above said predetermined level to said reservoir.

8. The combination with a gas engine, including a crank case, of a surplus oil reservoir, a vacuum producing pipe connected therewith, a connection between the crank case at the desired oil level therein and said reservoir through which oil or air is drawn into the reservoir from the crank case by the suction exerted upon said reservoir, and a second connection between a lower portion of the crank case and the reservoir through which oil is delivered from the reservoir to the crank case upon a reduction of vacuum in the reservoir.

9. The combination with a gas engine including a crank case, of a surplus oil reservoir, means for exerting a continuous suction thereon, a connection between the lower portion of said reservoir and the lower portion of said crank case through which oil flows from the reservoir to said crank case when vacuum in the reservoir is broken, and a connection between the upper portion of said reservoir and the crank case at the de-

sired oil level therein through which the vacuum in the reservoir is controlled by the oil level in the crank case.

10. An article of manufacture, comprising an oil reservoir, a suction pipe connected thereto, a pipe connected at one end to the upper portion of said reservoir and designed to communicate at its other end with a body

of oil at the desired oil level to be maintained, and a second pipe connected at one end with the lower portion of said reservoir and designed to communicate at its other end with said body of oil below said desired level.

WILLIAM A. EDWARDS.
